UNITED STATES PATENT OFFICE.

GEORGE B. CANNON, JR., OF BROOKLYN, AND FRANK W. HOWARD, OF NEW YORK, N. Y.

UMBRELLA.

1,356,263.

Specification of Letters Patent. Patented Oct. 19, 1920.

Application filed March 22, 1919. Serial No. 284,279.

To all whom it may concern:

Be it known that we, GEORGE B. CANNON, Jr., and FRANK W. HOWARD, citizens of the United States, and residents, respectively, 5 of Brooklyn and New York city, in the counties of King and New York and State of New York, have invented certain new and useful Improvements in Umbrellas, of which the following is a specification.

10 This invention relates to umbrellas and the general object of the invention is to produce an umbrella which can be produced most economically, the idea being that the umbrella may become available at very small 15 cost to persons who have been accidentally caught in the rain; one of the objects is to provide a very simple and inexpensive construction for the frame and stick of the umbrella which will dispense with the usual 20 joint connection between the ribs and the stick. By means of this invention the necessity for a connection between the umbrella cover and the stick is avoided and this feature particularly adapts the umbrella to include a cover of water proof paper, which is 25 relatively inexpensive. Further objects of the invention will appear hereinafter.

The invention consists in the combination of parts and features of construction to be 30 described hereinafter, all of which coöperate to produce a simple, inexpensive, and efficient umbrella.

In the drawing which fully illustrates 35 an embodiment of the invention,

Figure 1 is a vertical section through the open umbrella,

Fig. 2 is a side elevation of the umbrella in its folded state.

Fig. 3 is a plan of the umbrella shown in 40 Fig. 1.

Fig. 4 is a side elevation of the umbrella frame at one stage of its formation.

Fig. 5 is a plan showing another embodiment of the cover; and,

Fig. 6 is a plan showing one of the elements of the cover of the umbrella shown in 45 Fig. 5.

In the embodiment of the invention illustrated the ribs are so disposed that they will 50 maintain the umbrella cover in a taut condition without the use of a direct connection between the stick and the cover. To accomplish this the ribs 1 are attached so that they extend upwardly and outwardly 55 in a general radial direction from the stick 2 and present convex upper sides to support

and stretch the cover. Preferably a plurality of resilient wires 3 are twisted together to form the stick and these wires have integral extensions that form the ribs 1. 60

Means is provided for holding the ribs constrained when the umbrella is open. For this purpose a draw-string 4 is provided which extends continuously through eyes 5, which are formed respectively at the ends 65 of the ribs by bending the ends of the ribs upwardly. The edges of the cover 6 are secured in any suitable manner, such as by stitches to the eyes.

The ribs tend to assume a position parallel 70 with the axis of the stick. By releasing the knot and bow 7 of the draw-string, the ribs will be permitted to swing upwardly toward each other so as to close in around the cover 6, and a portion of the cover may then 75 be rolled around the ribs and the parts tied in this folded relation by the cord 4 as in Fig. 2.

The stick and frame may be formed by 80 producing a rod 8 of a plurality of twisted wires, for example three wires whose ends are left untwisted, see Fig. 4. The body of this rod is then twisted around itself to form a handle 9 and the stick 2, and the six extensions then come together to form the 85 ribs.

If desired the umbrella cover 6 may be 90 formed of a plurality of substantially triangular sections 10 which are glued or sewed together along radial seams 11.

A very simple form of cover may be employed in which the cover is produced of overlapping sections unattached together, see Fig. 5, in which the cover 12 is formed of two sections 12^a and 12^b which may be of 95 the character indicated in Fig. 6. Two such sections juxtaposed will form a square cover suitable for an umbrella having four ribs 13. Such a sectional cover adapts itself to the convex form of the frame produced by 100 the ribs and avoids the operation of connecting the sections together along their adjacent edges.

It is understood that the above specification describes only one embodiment of our 105 invention and we do not wish to be limited in the practice of our invention nor in our claims, to the particular embodiment set forth.

What we claim and desire to secure by 110 Letters Patent is:—

1. In an umbrella the combination of a

stick, a plurality of ribs extending upwardly and outwardly adjacent the stick, means for constraining said ribs to hold them flexed, and a cover supported on said ribs.

5 2. In an umbrella the combination of a stick, a plurality of ribs extending upwardly and outwardly adjacent the stick, means for constraining said ribs to hold them flexed, and a cover supported on said ribs, said 10 cover being attached to the ends of said ribs but unattached to said stick.

3. In an umbrella, the combination of a stick formed of a plurality of wires, said wires having integral resilient extensions 15 projecting outwardly from said stick when the umbrella is open and constituting the umbrella's ribs, means for constraining the extremities of said extensions to maintain the same in a flexed state, and a cover at- 20 tached to said extensions.

4. In an umbrella, the combination of a stick composed of a plurality of wires twisted together, said wires having integral resilient extensions projecting outwardly 25 when the umbrella is open, and constituting the umbrella ribs, a cord connecting the ends of said extensions to hold said extensions in a flexed state, and a cover disposed over said extensions and attached to said extensions 30 adjacent the extremities thereof.

5. In an umbrella the combination of a stick composed of a plurality of resilient wires twisted together, said wires having integral extensions branching outwardly from 35 the upper end of the stick when the umbrella is open, said extensions constituting ribs of the umbrella and having eyes formed at the extremities thereof, a draw-string extending through said eyes in succession for 40 holding the said ribs constrained and in a

flexed state, and a cover over said ribs and attached to the ends thereof.

6. In an umbrella, the combination of a plurality of resilient wires twisted together to form a stick, said wires having integral 45 extensions forming ribs projecting outwardly from the stick when the umbrella is open, and resiliently tending to assume a position lying substantially parallel with the axis of said stick, said ribs each having 50 an integral bend at its end forming an eye, a draw-string extending continuously through said eyes for holding said ribs in a curved state, and a cover disposed over said ribs and attached at its edges to said eyes. 55

7. In an umbrella, the combination of a stick composed of a plurality of resilient wires twisted together, and branching outwardly from the end of said stick when the umbrella is open, to form the umbrella ribs, 60 means for constraining the said extensions at their ends to hold them in a flexed state, and a cover formed of a plurality of overlapping relatively movable sections attached to the outer ends of said ribs. 65

8. In an umbrella, the combination of a plurality of resilient wires twisted together to form a rod, said rod being twisted upon itself to form the umbrella stick, the said wires having integral extensions projecting 70 outwardly from the end of said stick to form the umbrella ribs, means for constraining the ends of said ribs to hold the ribs in a flexed state, and a cover disposed over said ribs and attached to the ends of said ribs. 75

Signed at New York city, in the county of Kings and State of New York, this 18th day of March, A. D. 1919.

GEORGE B. CANNON, JR.
FRANK W. HOWARD.
